CLAIM

The ornamental design for a floor mat brush as shown and described.

DESCRIPTION

FIG. 1 is a perspective view of a floor mat brush, shown with environment;

FIG. 2 is a left side elevational view of the floor mat brush, with the environment removed;

FIG. 3 is a right side elevational view of the floor mat brush, with the environment removed;

FIG. 4 is a rear side elevational view of the floor mat brush, with the environment removed;

FIG. 5 is a front side elevational view of the floor mat brush, with the environment removed;

FIG. 6 is a top plan view of the floor mat brush, with the environment removed;

FIG. 7 is a bottom plan view of the floor mat brush, with the environment removed; and,

FIG. 8 is a perspective bottom view of the floor mat brush, with the environment removed.

The dash-dash broken lines shown in the drawings represent portions of the floor mat brush, form no part of the claimed design. The dot-dash-dot lines shown in the drawings represent environment, and form no part of the claimed design.

1 Claim, 8 Drawing Sheets
